United States Patent Office

Des. 181,113
Patented Oct. 1, 1957

181,113

WHEEL

John D. Smith, Selkirk, N. Y., assignor to Anti-Corrosive Metal Products Co., Inc., Schodack, N. Y., a corporation of New York

Application January 22, 1957, Serial No. 44,552

Term of patent 14 years

(Cl. D14—30)

Figure 1 is a top plan view of a wheel, embodying my new design;

Figure 2 is a side elevational view; and

Figure 3 is a transverse cross-sectional view taken substantially along the line 3—3 of Figure 1.

I claim:

The ornamental design for a wheel, substantially as shown.
